UNITED STATES PATENT OFFICE.

VICTOR L. MULLER, OF NORTH BERGEN, NEW JERSEY.

VALVE-OPERATING MECHANISM.

Application filed June 27, 1921. Serial No. 480,584.

To all whom it may concern:

Be it known that I, VICTOR L. MULLER, a citizen of the United States, and a resident of North Bergen, in the county of Hudson and State of New Jersey, have invented new and useful Improvements in Valve-Operating Mechanisms, of which the following is a specification.

This invention relates in general to valve-operating mechanisms, and more particularly to a mechanism adapted for distance operation whereby a valve, such for instance as are used in overhead pipe lines, can be opened and closed from a point distant from the valve.

The objects of the invention are to provide a mechanism of the character described embodying novel features of construction which is strong, durable and reliable in operation; to provide an improved valve-operating mechanism of this character by means of which a valve may be both opened step by step and closed by mere straight pulls upon a cord, chain or the like; to provide such a mechanism by means of which the valve can be fully opened by one continuous pull on the cord or chain; to provide for this purpose a rotatable substantially elliptical cam engaging a sliding valve stem, and improved means for rotating said cam by pulls on said cord or chain; to provide in combination with such a cam, an operating lever having radial ribs or teeth on one side thereof to engage corresponding teeth on the side of the cam whereby swinging of the operating lever in one direction causes engagement of the teeth thereon with the teeth on the cam to rotate said cam, said shoulders on the lever riding over the shoulders on the cam when swinging in the opposite direction; to provide mechanism of the character described including a novel, strong and durable support which may be easily mounted on a valve casing, and to obtain other results and advantages as may be brought out by the following description.

Referring to the accompanying drawings, in which like numerals of reference indicate the same parts throughout the several views,

Figure 1 is a side elevation of a valve operating mechanism constructed in accordance with my invention;

Figure 2 is a top plan view thereof;

Figure 3 is a vertical sectional view taken

on the line 3—3 of Figure 3 looking in the direction of the arrow, showing the valve in closed position;

Figure 4 is a fragmentary view of the end 60 of the valve stem and the actuating cam showing the position of the cam to open the valve, and

Figure 5 is a vertical sectional view taken on the line 5—5 of Figure 2 looking in the 65 direction of the arrows.

Specifically describing the present embodiment of my invention the numeral 1 designates a valve casing provided at opposite ends thereof with inlet and outlet openings 70 2 and 3, respectively, which are separated by a transverse partition or diaphragm 4 in which is formed a valve port 5 provided with a valve seat 6. A valve 7 cooperates with said valve seat 6, and is mounted upon a valve stem 8 which is slidably mounted transversely of the valve and passes outwardly through a neck 9 upon which is threaded a bonnet 10 which serves as a stuffing box. The valve 7 is normally seated 80 by a coil spring 11 which is interposed between the underside of the valve and a removable cap 12 screwed on the side of the valve opposite the neck 9, said cap being provided with a guide socket 13 to guide 85 the lower end of the valve stem 8.

A substantially U-shaped bracket 14 is mounted upon the neck 9 of the valve casing, the base of said bracket being formed with an opening 15 which fits around the 90 neck 9, and a nut 16 being provided for clamping the bracket against the valve casing. The outer ends of the arms of the bracket are formed with bearings 17 in which is journaled a transversely extending 95 shaft 18 which is disposed slightly beyond the outer end of the valve stem 8. A cam 19 is fixedly mounted on the shaft 18 adjacent the end of the valve stem, the said cam being substantially elliptical in shape 100 and being mounted axially upon the shaft, so that when the minor axis of the cam is parallel with the valve stem the two long sides of the cam will slightly clear the valve stem and allow the valve to close. One end 105 of the cam 19 is formed with an integral or rigidly connected disc-like portion 20 which is formed upon one side thereof with a plurality of radially disposed shoulders or teeth 21, the said teeth being preferably 110 four in number and arranged at angles of substantially 90° apart.

For the purpose of rotating the cam 19 an operating disk 22 is rotatably mounted on the shaft 18 adjacent the cam 19, the said disk being provided at the side thereof adjacent the disk portion 20 of the cam with a boss 23 formed with a plurality of radially disposed shoulders or teeth 24 similar to the teeth of the cam and oppositely arranged thereto so that the teeth of the cam and the operating disk will engage each other to rotate the cam when the operating disk is rotated in one direction. The operating disk is provided with a substantially radially projecting arm 25 to which is connected a cord or chain 26 which is normally suspended from said arm so as to be within the reach of an operator. When the operating disk 22 is rotated in the direction of the arrow on Figure 1, it will be observed that the teeth 24 thereof will operatively engage the teeth 21 on the cam so as to rotate the same, the teeth 24 riding backwardly over the teeth 21 of the cam when the operating disk is rotated in the opposite direction. The operating disk is formed at its edge with a pair of stop notches 27, 28 which are adapted to cooperate with a stop rod 29 fixedly connected to the arms of the bracket and extending between the same, the said stops being disposed slightly more than 90° apart so that when the operating disk rotates backwardly a slight lost motion is allowed between the teeth of the disk and the cam, as shown in Figure 2, so as to insure the teeth 24 freely passing over the teeth 21. The engagement of the stop notch 28 with the stop rod 29 limits the backward movement of the operating disk 22, while engagement of the stop notch 27 with the rod 29 limits the forward movement of the operating disk. A helical spring 30 is interposed between the operating disk 22 and the adjacent arm of the bracket, one end of said spring being fixed to the said bracket and the other end thereof engaging under the operating arm 25, whereby said spring serves to return the operating disk to its normal position, as shown in Figure 1, after actuation of the cam 19. The said spring also constantly influences the operating disk toward the teeth 21 on the cam so as to insure engagement of the teeth of the disk and the cam on the forward movement of the disk. With this construction it will be observed that when the operating disk 22 is rotated from the position shown in Figure 1, until the stop notch 27 engages the rod 29, the cam 19 will be rotated from the position shown in Figure 3 to that shown in Figure 4 so as to slide the valve stem 8 inwardly of the casing and open the valve 7. To prevent backward rotation of the cam 19 a ratchet wheel 31 is rigidly connected to the cam and is adapted to be engaged by a pawl 32 pivotally mounted at 33 on one arm of the bracket 14, said pawl being influenced into engagement with the teeth of the ratchet by a spring 34. This ratchet 31 and pawl 32 enable the valve to be held in partially opened position by the cam 19. A slight pull on the cord 26 rotates the cam only a sufficient distance to partially open the valve, and the pawl 32 engaging the ratchet 31 prevents backward rotation of the cam and thus holds the valve in open position. After the valve has been completely opened, as shown in Figure 4 of the drawings, another pull on the cord 26 will rotate the cam so that the valve will be closed under the influence of its spring.

In operation a valve actuating mechanism of this character is subjected to considerable strain especially on the shaft and the supporting bracket, and with my construction the shaft 18 is supported at both ends outside the cam and operating lever and the mechanism is balanced in the bracket so that possibility of bending of the shaft and bracket incident to strain thereon due to pulls on the cord 26 is eliminated.

While I have shown and described one possible embodiment of my invention, it will be understood that this is mainly for the purpose of illustrating the principles thereof, and that many modifications and changes can be made in the detail construction of the operating mechanism without departing from the spirit or scope of the invention. Therefore, I do not desire to be understood as limiting myself except as required by the following claims when construed in the light of the prior art.

Having thus described the invention, what I claim is:

1. The combination with a valve casing having a neck thereon and a spring closed valve therein having a sliding stem projecting from said neck, of a U-shaped bracket having an opening in its base to fit over said neck for securing said bracket to said valve casing, a shaft rotatably journaled at its ends in the arms of said bracket and extending transversely of the end of said valve stem, a cam mounted on said shaft to slide said valve stem to open said valve when said shaft is rotated a part of a complete revolution in one direction and permit said valve to close upon completion of the revolution of said shaft in said direction, and means for rotating said shaft.
2. The combination with a valve casing having a neck thereon and a spring closed valve therein having a sliding stem projecting from said neck, of U-shaped bracket having an opening in its base to fit over said neck for securing said bracket to said valve casing, a shaft rotatably journaled at its ends in the arms of said bracket and extending transversely of the end of said valve stem, a cam mounted on said shaft to slide said

- valve stem to open said valve when said shaft is rotated a part of a complete revolution in one direction and permit said valve to close upon completion of the revolution 5 of said shaft in said direction, pawl and ratchet means for preventing rotation of said shaft in the opposite direction to hold said valve in open position, and means for rotating said shaft.
- 10 3. The combination with a valve casing having a neck thereon and a valve therein having a sliding stem projecting from said neck, of a U-shaped bracket having an opening in its base to fit over said neck for securing said bracket to said valve casing, a cam rotatably journaled in the arms of said bracket to actuate said valve stem and having ratchet teeth, an operating member journaled on said bracket coaxially with said cam and 15 rotatable relatively thereto in opposite directions, said operating member having teeth to cooperate with the teeth on said cam to rotate said cam upon rotation of said operating member in one direction, said teeth of 20 the operating member sliding idly over the teeth of said cam upon rotation of said operating member in the opposite direction, and means for preventing rotation of said cam in the last-mentioned direction.
- 25 4. The combination with a valve casing having a neck thereon and a valve therein having a sliding stem projecting from said neck, of a U-shaped bracket having an opening in its base to fit over said neck for securing said bracket to said valve casing, a cam rotatably journaled in the arms of said bracket to actuate said valve stem and having ratchet teeth, an operating member journaled on said bracket coaxially with 30 said cam and rotatable relatively thereto in opposite directions, said operating member having teeth to cooperate with the teeth on said cam to rotate said cam upon rotation of said operating member in one direction, said teeth of the operating member sliding idly over the teeth of said cam upon rotation of said operating member in the opposite direction, spring means for 35 preventing rotation of said cam in the last-mentioned direction.
- 40 5. The combination with a valve casing having a neck thereon and a spring closed valve therein having a sliding stem projecting from said neck, of a U-shaped bracket having an opening in its base to fit over said neck to mount the bracket on said valve casing, a substantially elliptical cam 45 rotatably journaled in the arms of said bracket to actuate said stem to open said valve, said cam permitting said valve to be spring closed when the minor axis of the cam is substantially in alinement with said stem and said cam opening said valve as the cam is rotated to bring the major axis of the cam into alinement with said stem, and means for 50 rotating said cam in the last-mentioned direction, a ratchet on said shaft, and a pawl on said bracket to engage said ratchet to prevent rotation of said cam in the last-mentioned direction.
- 55 6. The combination with a valve casing having a neck thereon and a valve therein having a sliding stem projecting from said neck, of a U-shaped bracket having an opening in its base to fit over said neck to mount the bracket on said valve casing, a substantially elliptical cam 60 rotatably journaled in the arms of said bracket to actuate said stem to open said valve, said cam permitting said valve to be spring closed when the minor axis of the cam is substantially in alinement with said stem and said cam opening said valve as the cam is rotated to bring the major axis of the cam into alinement with said stem, and means for 65 rotating said cam in the last-mentioned direction.
7. A valve operating mechanism for sliding stem valves, including a U-shaped bracket having an opening in its base adapted to fit over the neck of a valve casing, a shaft rotatably journaled at opposite ends in the arms of said bracket, a substantially elliptical cam fixedly mounted on said shaft between the arms of said bracket to actuate the valve stem to open the valve, said cam permitting said valve to be spring closed when the minor axis of the cam is substantially in alinement with said stem and said cam opening said valve as the cam is rotated to bring the major axis of the cam into alinement with said stem, said cam having teeth, an operating member rotatable on said shaft coaxially with and relatively to said cam in opposite directions, said operating member having teeth to engage the teeth on said cam to rotate the cam in one direction, said teeth of said operating member being adapted to slip over the teeth of the cam upon movement of said member in the opposite direction, spring means for rotating said member in the last-mentioned direction, a ratchet on said shaft, and a pawl on said bracket to engage said ratchet to prevent rotation of said cam in the last-mentioned direction.
